UNITED STATES PATENT OFFICE.

RICHARD WEBB BURNETT, OF MONTREAL, QUEBEC, CANADA.

CAR-ROOF.

1,196,660.

Specification of Letters Patent. Patented Aug. 29, 1916.

Application filed November 7, 1912. Serial No. 730,003.

To all whom it may concern:

Be it known that I, RICHARD WEBB BURNETT, a resident of the city of Montreal, in the Province of Quebec and Dominion of Canada, have invented certain new and useful Improvements in Car-Roofs; and I do hereby declare that the following is a full, clear, and exact description thereof.

My invention relates particularly to the type of roofs having carlines of inverted U-form and consists, broadly speaking, of a carline constructed of T-cross-section with downwardly turned flanges and having hangers depending from the web or leg of the T for supporting bearing plates locked in place with sufficient clearance between their upper surfaces and the flanges of the carline to confine the upturned side edges of the roof sheets without abrasion.

For full comprehension, however, of my invention reference must be had to the accompanying drawings forming a part of this specification in which similar reference characters indicate the same parts, and wherein:

Figure 1 is a transverse sectional view of portions of a roof and upper portion of the side of a car containing this invention; Fig. 2 is a transverse vertical sectional view of my improved carline taken on line A A Fig. 1; Fig. 3 is a horizontal sectional view taken on line B B Fig. 2, Fig. 4 is a detail perspective view of the means for suspending the roof-sheets from the carline, and Fig. 5 is a horizontal sectional view taken on line X X Fig. 1.

The main supporting members of my improved roof consist of a series of carlines of T-cross-section and having their side flanges 4 turned down to protect the upturned side edges of the roof sheets. A series of hangers 5 are riveted at their upper ends to the webs or legs 25 of the carlines while their lower ends carry plates 6. These plates extend slightly beyond the width of the carlines and in length are sufficiently greater than the width of the hangers to impart the required rigidity to them to support the roof-sheets. In order to support these plates, the hangers are slotted at 15 the slots extending upwardly to approxi-

mately the lower edge of the web or leg of the T and wedge-shaped pins driven into these slots rigidly clamp these plates there between the web or leg of the carline.

The roof-sheets are supported, as before mentioned, upon the bearing plates and have their upturned side edges overhung by the turned down flanges of the T, sufficient space between the turned down flanges and the bearing plates affording the necessary clearance to accommodate the roof-sheets without abrasion thus permitting them to move freely during the working of the car.

In assembling the parts of my invention the hangers are riveted to the webs or legs of the T before the flanges are turned down then the roof-sheets are held in place having their upturned side edges within the turned down flanges of the carline the bearing plates are slipped on and the pins driven and their ends turned down to hold them in place.

The carlines are connected at their ends to the side plates of the car by having the ends of their flanges 4 turned laterally as at 10, Fig. 5 and perforated to receive bolts 12, the sheets being slotted to accommodate distance pieces 14 through which the bolts project.

What I claim is as follows:

1. The combination with a carline of T-cross-section having turned-down flanges, of a series of hangers fastened to and depending from the leg of the T, a series of bearing plates detachably engaging the hangers, means whereby one of the bearing plates is supported by each hanger, and roof sheets having turned-up side edges supported by a plurality of said bearing plates with the upturned side edges within the turned-down flanges of the carline, said sheets being spaced from said carline.

2. The combination with a carline of T-cross-section having down-turned flanges, of a hanger fastened to and depending from the leg of the T, a bearing plate detachably engaging the hanger and having its upward movement limited by the lower edge of the leg of the T, taper pins inserted beneath the bearing plates and engaging apertures therein for holding the bearing plates from

downward movement, and roofing sheets having upturned side edges supported on said bearing plates with the upturned side edges within the turned, down flanges of the carline, the roofing sheets having a limited freedom of movement.

In testimony whereof I have signed my

name to this specification in the presence of two witnesses.

Montreal, November 2nd, 1912.

RICHARD WEBB BURNETT.

Witnesses:

GORDON G. COOKE,

E. R. PITTS.
